THERMOSTATICALLY CONTROLLED ELECTRIC IRON FOR DRY AND STEAM IRONING

Alan Bate, Riverton, Conn., assignor to The Winsted Hardware Manufacturing Company, Winsted, Conn., a corporation of Connecticut

Application February 17, 1948, Serial No. 8,861

8 Claims. (Cl. 38—77)

1

This invention relates to new and useful improvements in sadirons and has particular relation to an electric steam iron and is concerned in part with the application of the principle disclosed in my application Serial Number 781,442 filed October 22, 1947, now Patent No. 2,573,174, dated October 30, 1951, to a household or more conventional type of electric iron.

An object of the invention is to provide an electric steam iron including a sole plate and a flash boiler on one side of said sole plate and including a casting having a circuitous passage therethrough and adapted to receive water and discharge steam.

Another object of the invention is to provide an electric steam iron including a fixed handle and a perforated sole plate connected to a flash boiler in which steam is made under external water pressure supplied to a valve on the iron at the boiler intake.

Another object is to provide an electric steam iron having the characteristics above set forth and further including certain improved features of construction whereby the iron is of neat and attractive appearance and adapted for long useful life.

Other objects and advantages of the invention will become apparent from a consideration of the following detailed description taken in connection with the accompanying drawings wherein a satisfactory embodiment of the invention is shown. However, it is to be understood that the invention is not limited to the details disclosed but includes all such variations and modifications as fall within the spirit of the invention and the scope of the appended claims.

In the drawings:

Fig. 1 is a side elevational view showing an electric steam iron constructed in accordance with the invention and hooked up ready for use;

Fig. 2 is a central longitudinal sectional view through the iron of Fig. 1;

Fig. 3 is a transverse sectional view taken as along the line 3—3 of Fig. 2;

Fig. 4 is a top plan view of the sole plate thermostatic control and boiler assembly;

Fig. 5 is a bottom plan view of the flash boiler; and

Fig. 6 is a top plan view of the sole plate and thermostatic control assembly, the boiler being omitted.

Referring in detail to the drawings, my improved electric steam iron, generally designated 10, comprises a sole plate 11 of steel against the upper side of which is secured a flash boiler 12

5

and on the upper side of such flash boiler is a suitable electrical heating element or unit 13 against the upper side of which is located a pair of heat insulating sheets 14, of asbestos or the like. The heating element or unit 13 is held in good thermal contact with the upper side of the flash boiler 12 by the asbestos pads 14 which serve to distribute the pressure of a metal pressure plate 15 pressing against the upper side of the uppermost of said insulating pads.

Over the assembly described there is disposed a closure shell or casing 16 of sheet metal the same being held in place as by hollow screws 17 and 18 passing through the shell and threaded to studs

19 and 20 having their lower ends secured to the sole plate. The iron is to be manipulated by a handle 21 of any suitable material but preferably of an insulating material and such handle has its forward end secured to the forward portion

15 of the shell or casing 16 through a heat baffling arrangement 22 and the rear portion of said handle is secured to the rear portion of the shell or casing 16 through a suitable heat baffling arrangement 23. The rear portion of the handle 21 is hollowed out as at 24 and such hollow portion includes side walls 25 and 26. The purpose of this construction will later appear.

20 The circuit to the heating element 13 is controlled by a thermostatic or thermally operated switching means generally designated 32 and such means may be any of those disclosed in my application Serial Number 715,561 filed December 11, 1946, now Patent No. 2,537,808, dated January 9, 1951. As here shown, the switching means

25 comprises a pair of arms 27 and 28 mounted on the respective studs or posts 19 and 20 and carrying contact buttons as shown. The contact arms are, of course, insulated from the posts and connected with the element 13. Below the lower contact arm 27 there is a bowed element 29 held in bowed position by having its extremes anchored or secured to or in engagement with lower portions of the posts or studs 19 and 20.

30 The bowed element 29 has a small coefficient of expansion as compared with that of the sole plate whereby, as the sole plate becomes heated and the studs 19 and 20 move apart, the bowed element tends to flatten and this permits opening of the switch comprising the arms 27 and 28. Thereafter as the sole plate cools and contracts, the studs 19 and 20 are moved toward one another

35 causing an increase in the curvature or bowing of the element 29 so that the switch arm 27 is forced upwardly to engage its contact button with that

40 of the posts 19 and 20.

45

45

50

55

of the switch arm 28 to again close the circuit to the element 13.

Any or the usual adjustment for controlling the opening and closing of the switch by the thermal means may be employed, such an adjustment being shown in my application above referred to and in the present instance being designed for manipulation by means of a hand piece 30 located at the upper side of the shell 16 and preferably under the hollow of the handle 21. It is noted that on the studs 19 and 20, below the hollow screws 17 and 18, are nuts 31 and these nuts are tightened to clamp the pressure plate 15 against the insulating pads 14 to secure the assembly prior to the disposition of the shell or closure thereover. On said studs at the under side of the pressure plate 15 are other nuts 31a for securing the switching arms 27 and 28 in position.

The thermal or thermostatic switch assembly generally designated 32 is shown as assembled or mounted on the sole plate without the addition of any other parts in Fig. 6. The sole plate has a series of ports 33 extending from its upper side through its lower side and as best illustrated in Fig. 6, a number of these ports lead into elongated depressions or channels 34 formed in the underside of the sole plate. As will later more clearly appear, the ports 33 serve as conduits to conduct steam to the underside of the sole plate.

The flash boiler 12 comprises a body 35 in the form of an aluminum casting and of substantially the contour of the upper side of the sole plate 11. The aluminum casting 35 has a circuitous passage cast therein. As shown, this passage is formed by a substantially flat coil of tubing 36, the inlet end portion 37 of which extends above the casting and rearwardly thereof and preferably has its free end flanged as at 38. The passage formed by the tubing 36 also includes a discharge end portion 39 located in a pocket or cavity 40 formed in the underside of the casting 35 towards the forward or toe end portion thereof. Boiler 12 and the cast body portion 35 has an opening 41 formed entirely therethrough and, as shown, such opening is somewhat in the shape of a cross and is located within the passageway formed by the flat coiled tube 36.

When making the assembly, after the thermostatic or thermal switch means 32 is mounted on the upper side of the sole plate, a suitable sealing gasket 42 (Fig. 2) is disposed on the recessed flat surfaces 43 surrounding the pocket 40 of the casting 35 and then the casting is reversed from the position of Fig. 5 to that of Fig. 4 and is disposed against the upper side of the sole plate. The boiler and the sole plate are then secured together in the desired manner, preferably as by means of three screws 44 (Fig. 4) which pass through openings 45 in the boiler or casting 12 (Fig. 5) and are threaded into tapped openings 46 (Fig. 6) in the upper side portion of the sole plate 11. Thereafter, the heating element is located and the parts 14 and pressure plate 15 are positioned and secured in place.

Through the side wall 25 of the hollow handle portion, an electrical cord 47 is carried as through a rubber or other flexible protecting device 48 and at the inner side of the wall 25 such cord may pass through a washer or the like 49 and have a strain reliever 50 applied thereto. Within the recess or hollow portion 24 of the handle, the wires of the cord 47 are separated and are connected with binding posts 51 and 52 on conductor strips 53 and 54 suitably connected with the ele-

ment 13, such connection being as through the thermal or thermostatic switch means 32.

Also mounted on the wall 25 is a valve, generally designated 55, comprising essentially a casting 56 having a valve seat 57 and a needle valve 58 carried by or including a relatively long stem 59 which passes through the wall portion 26 of the handle and at the outer side of the latter is equipped with a handle or finger piece 60 for manipulation of the valve. A flexible conduit 61, as in the form of a length of rubber hose or the like, is connected with the inlet 62 of the valve 55 and this connection may be made through a flexible protecting piece or housing 63. The outlet from the valve 55 is shown at 64 and comprises a length of tubing which, through a union or similar coupling 65, is connected with the inlet portion 37 of the boiler tube or passageway 36.

As best shown in Fig. 3, the flared end portion 38 of the inlet 37 is used in making the connection through the union 65. The tubing 61 is preferably of a convenient length and at its outer end is connected with or provided with a coupling, generally designated 66, which may be of the general type disclosed in the now abandoned application of Harry M. Voglesonger, Serial Number 8,937 filed February 17, 1948.

Conductor cord 47 will also be of convenient length and at its outer end is provided with a suitable or desired plug cap 67. For convenience in handling the cord 47 and the tube 61, small clips may be used to hold them together for the greater portion of their length, one of such clips being shown at 68.

When the iron of the invention is to be used, the plug cap 67 is plugged into a suitable electrical outlet and the coupling 66 is connected to a tap or faucet, a portion of one of which is shown at 69 in Fig. 1. From this tap or faucet, water 40 will be supplied under city pressure. The thermostatic or thermal switch is adjusted or dialed to the desired setting by operation of the finger or hand piece 30 and the iron 10 is then ready for use.

The faucet 69 will have its valve (not shown) open to provide a constant or steady dribble and any excess pressure will be relieved through a regulator feature of the coupling 66, all as disclosed in the above mentioned application of Harry M. Voglesonger. If steam is desired, the needle valve 58 is opened by manipulation of the knob or finger piece 60 and water under pressure of the city mains is forced into the passageway provided by the metal tubing 36 cast into the aluminum casting 35, said casting and tube comprising the present flash boiler.

Heat from the heating unit or element 13 on the upper side of the flash boiler converts the water into steam which, passing through the entire length of the tube, enters the chamber or pocket 40 and from the latter passes out through the ports 33 to the underside of the sole plate. Whenever steam is not desired, it is merely necessary to close the valve 55.

An iron constructed as described has many advantages over the tank type of steam iron. In the present iron there is not the bulk to be found in the tank type of steam iron and further, with the present construction, the supply of steam is practically inexhaustible as there is no occasion for refilling a tank or the like. Additionally, the present iron has the ability to supply copious quantities of steam whether dry or wet. Practically instantly the valve 55 may be closed, adapting the iron for dry ironing. Just

as readily, the valve may be opened adapting the iron for steam ironing.

As soon as the sole plate 11 is hot, the iron is ready for use as a steam iron to instantly convert water into steam. The volume of steam is controlled by the valve 55 and thus the iron may deliver variable quantities of steam. Since either the steam system is open to an inexhaustible supply of water or the iron is being used dry, it includes a safety feature in that there is no occasion for steam explosion.

The iron of the invention is adapted for producing steam when the iron is hot even though the iron is dialed to the higher ranges since contrary to the previous structures the steam in the present instance is not produced before the water has a chance to move away from the valve 55 and so steam in large quantities may be produced. Depending on the volume of water supplied, the steam passing out through the ports 33 may be very wet steam or it may be superheated and therefore dry or invisible steam.

With the described construction, when the iron is dialed for its highest heat, the needle valve 58 may be opened wide to allow the heating element 13 to evaporate as much water as is within its "continuous-on" power to do so. That is, all the electrical energy can be diverted into evaporated water whereas in other constructions the maximum ability to convert steam into water is limited by the design and not by the available power. This makes a substantial difference since the iron herein disclosed will evaporate about one ounce of water per minute whereas in constructions previously provided the capacity is about one-third of that of the present iron. Thus, the iron of the invention is capable of producing large quantities of steam obviating the necessity for the use of a pressing cloth.

With the present construction, it will be seen that steam is produced under water pressure and not steam pressure and that the present construction has the ability to translate all of the available electric energy into heat of evaporation. The described iron is easily assembled since the flash boiler 12, for the purpose of assembly, comprises but a single element; namely, the casting 35 having the circuitous passageway provided therein by the casting therein of the flat coiled tubing 36. Additionally, it will be understood that steam is made in the boiler under external water pressure, such as city pressure, supplied to the valve 58 located on the iron and controlling the intake to the boiler.

Having thus set forth the nature of my invention, what I claim is:

1. In an electric steam iron, a sole plate having ports extending through it from its upper side to its under side, a boiler on the upper side of said sole plate and conforming generally to the contours of said upper side, an electrical heating element on top of said boiler, thermostatically controlled switch means supported on said sole plate above the mid portion thereof and directly responsive to the temperature of said sole plate, said boiler and said heating element having aligned opening through their mid portions accommodating said switch means, said switch means connected in and controlling the circuit of said heating element, said boiler having a passage therethrough including an end for receiving water under pressure and a discharge end communicating with said ports to supply steam thereto.

2. In an electric steam iron, a sole plate hav-

ing ports extending through it from its upper side to its under side, a boiler on the upper side of said sole plate and having a passage therethrough including an inlet and an outlet communicating with said ports, an electric element on the upper side of said boiler for heating said boiler and the contents of said passage, a closure shell over said boiler and heating element and connected to said sole plate, a handle fixed to said shell, a conductor cord entering said handle and having its wires connected with said electric element, a valve mounted in said handle and connected with the inlet of said passage, a flexible tube coupled at one end to said valve for supplying water thereto and adapted to have its other end coupled to a source of water under pressure, said valve including a casing having a valve seat, a needle valve in said casing and having threaded engagement with a portion thereof for adjustment toward and from said seat and whereby the valve will remain in adjusted position, and a hand piece connected with said needle valve for manual adjustment of the same.

3. In an electric steam iron, a steel sole plate having ports extending through it from its upper side to its under side, a boiler on the upper side of said sole plate and comprising a flat aluminum casting having a flat circuitous passage therein, said casting being of the general contour of said sole plate, means securing said casting against the upper side of said sole plate, an electric heating element against the upper side of said casting, means whereby water may be supplied to said passage, and said passage having a discharge communicating with said ports.

4. In an electric steam iron, a steel sole plate having ports extending through it from its upper side to its under side, a boiler on the upper side of said sole plate and comprising a flat aluminum casting having a flat circuitous passage therein, said casting being of the general contour of said sole plate, means securing said casting against the upper side of said sole plate, an electric heating element against the upper side of said casting, an insulating pad against the upper side of said electric heating element, a pressure plate against the upper side of said pad whereby pressure is distributed over said pad and element and the latter is secured in good thermal contact with said boiler, means whereby water may be supplied to said passage, and said passage having a discharge communicating with said ports.

5. In an electric steam iron, a sole plate having ports extending through it from its upper side to its under side, a pair of studs secured to said sole plate and extending upwardly therefrom, a thermostatically controlled switch means mounted by said studs and directly responsive to sole plate temperature, a substantially flat boiler on the upper side of said sole plate and generally conforming to its contours, a heating element on the upper side of said boiler, said boiler and heating element having registering openings accommodating said studs and switch means, said switch means connected in circuit with and controlling said heating element, said boiler having a passage therethrough including receiving and discharge ends, means to connect said receiving end to a source of water under pressure, said discharge end being located to supply steam to said ports, a shell over said sole plate, boiler and heating element, a handle attached to said shell, and means passing through said shell and threaded to said studs to secure said shell to said sole plate.

6. In an electric steam iron, a sole plate having ports extending through it from its upper side to its under side, a pair of studs secured to said sole plate and extending upwardly therefrom, a thermostatically controlled switch means mounted on said studs and directly responsive to sole plate temperature, a substantially flat boiler on the upper side of said sole plate and generally conforming to its contours, a heating element on the upper side of said boiler, said boiler and heating element having registering openings accommodating said studs and switch means, said switch means connected in circuit with and controlling said heating element, said boiler having a sinuous passage therethrough including receiving and discharge ends, means to connect said receiving end to a source of water under pressure, said discharge end being located to supply steam to said ports, a shell over said sole plate, boiler and heating element, and a handle attached to said shell. 15 20

7. The device of claim 6 wherein the boiler is in

the form of a casting and the sinuous passage therethrough is defined by flat coiled tubing cast therein.

8. The device of claim 7 wherein the sole plate is of steel and the boiler casting of aluminum.
